Primary Examiner — Darlington Ly*Assistant Examiner* — Nasim Abdulaziz Ali(74) *Attorney, Agent, or Firm* — The Rapacke Law Group P.A.(57) **CLAIM**

The ornamental design for a balance bike, as shown and described.

DESCRIPTION

FIG. 1 is a perspective view of the balance bike, showing the new design;

FIG. 2 is a front elevational view of the balance bike thereof; FIG. 3 is a rear elevational view of the balance bike thereof; FIG. 4 is a right side elevational view of the balance bike thereof;

FIG. 5 is a left side elevational view of the balance bike thereof;

FIG. 6 is a top plan view of the balance bike thereof; and, FIG. 7 is a bottom plan view of the balance bike thereof. The broken lines in the drawings illustrate portions of the balance bike that form no part of the claimed design.

1 Claim, 7 Drawing Sheets(56)
